COMBINED BANK AND STAND

Siegfried Hoffmann, New York, N. Y.

Application September 1, 1950, Serial No. 12,023

Term of patent 14 years

(Cl. D34—11)

To all whom it may concern:

Be it known that I, Siegfried Hoffmann, a citizen of no country, residing in New York city, county of New York, and State of New York, have invented a new, original, and ornamental Design for a Combined Bank and Stand, of which the following is a specification, reference being had to the accompanying drawing, forming part thereof, wherein,

The characteristic features of my design reside in the portions shown in full lines in the drawing.

I claim:

The ornamental design for a combined bank and stand, substantially as shown and described.

SIEGFRIED HOFFMANN.
